BELL RINGING MECHANISM

Ralph A. Light, Cynwyd, and Joseph W. Price, Jr.,
Philadelphia, Pa., assignors to The United
States Metallic Packing Company, Philadel-
phia, Pa., a corporation of Pennsylvania

Application January 15, 1935, Serial No. 1,893

3 Claims. (Cl. 121—2)

This invention relates generally to bell ringing mechanism of the kind disclosed in our prior Patent No. 1,942,360, dated January 2, 1934, and more particularly to the type featured in our co-pending application for a further patent, filed September 8, 1934, Serial No. 743,186.

In the disclosure above cited, the weight of the bell has been relied upon for returning the actuator piston by coaction of the cam with the point of said piston, but it has been found in practice that the inertia of the bell frequently failed to fully return the actuator to its proper starting position. This disadvantage has been more especially noticeable in connection with the ringing mechanism of light weight bells, wherein the bell frequently came to rest in a position at an inclination to the vertical, or out of plumb, due to incomplete retraction of the actuator piston, with the result such condition rendered it practically impossible to restart the ringing mechanism.

The primary object of the present invention is to overcome the noted disadvantage in a simple and effective manner, with preassurance that the actuator piston is automatically retracted to proper starting position, while the bell is left free to swing into, or stop in, plumb position subsequent to each ringing cycle.

With the stated and other objects in view, as will in part hereinafter become apparent and in part be stated, the instant invention comprises novel structural features, combinations, and arrangements of parts as subsequently specified and claimed.

In the drawing:

Fig. I is a longitudinal plan section of a bell ringing mechanism including the present invention.

Fig. II is a part elevational and part vertical section, taken approximately as indicated by the arrows II—II on Fig. I; and,

Fig. III is a schematic view, partly in section, illustrating the positional relationship of various elements of the bell ringing mechanism during operation of the latter.

Referring more in detail to the drawing, our improved bell ringing mechanism generally is of the construction more particularly featured in our co-pending application hereinbefore mentioned, that is to say it comprises a back-plate 1 permanently secured to one of the bell bearings 2. To the back-plate 1 is removably secured as by bolts 3, the housing 4 having a cylindrical portion 5, closed in at its outer end with a cupped-head 6. Secured to the bell-trunnion 7 is a lobe-shaped cam 8 having convexed edges 9, 10, substantially

merging into a circular hub 11, said convexed edges alternately coacting with the "tip" 12 of a tapering projection 13, at the forward end of an actuator piston 14, reciprocative in the cylindrical portion 5 aforesaid. Rotation of the piston 14 is prevented by a screw-stud 15 having its reduced end 16 projecting into a longitudinal groove 14' in said piston; while 17 designates a hollow valve for controlling admission and exhaust of the motivating medium by way of inlet and exhaust ports 18, 19, respectively; said inlet port having an associated pressure-regulating valve 20: all of the foregoing forming no part of the present invention and being merely referred to by way of better explaining the present improvements.

As hereinbefore stated, our present improvements have reference to means whereby the actuator piston 14 is automatically retracted to correct position for restarting after each bell-ringing cycle. To this end it is to be firstly noted that the actuator piston 14 is connected with the hollow valve 17 by means of a valve stem 21 threadedly engaged axially into said piston and immovably secured by a diametric pin 22, in an obvious manner. This valve stem 21 differs from the prior structures of our patented and co-pending application disclosures, in that it is provided with an outwardly-extending and diametrically-enlarged portion 23, affording a shoulder 24 adapted to engage the apertured end 25 of the hollow valve 17, to move the latter forward in effecting closure of the inlet port 18. The valve stem enlarged portion 23 is also provided with a head 26 having a cross groove 27, whereby said stem is suitably screwed into the actuator piston 14, as readily understandable by those conversant with the art.

Concentrically within the housing cylindrical portion 5 is a cupped retainer device 28 having its inner end wall 29 apertured at 30 for slidable passage of the valve stem enlarged portion 23, and at its outer end a circumferential flange 31 for clamping engagement between a shoulder 32 in said cylindrical portion 5 and the confronting end of the cupped head 6. Intermediate the head 26 of the valve stem enlargement 23 and the inner end wall 29 of the cupped retainer device 28 is a spring 33 in compression, for a purpose later on explained.

Operation of bell ringing mechanism, including the improvements described in the two preceding paragraphs, substantially conforms with the disclosure in our previously mentioned patent and co-pending application, but with the following characteristic distinction. In the cycle of

bell ringing operation the piston 14 initially moves toward the lobe cam 8 under pressure exerted by the motivating medium admitted to the cylinder 5 through the inlet port 18, until the shoulder 24 of the valve stem contacts the apertured end of the hollow valve 17, whereupon the latter is moved along with the piston 14 to close the inlet port 18 and open the exhaust port 19. Incident to movement of the valve 17 as just described, it will be obvious that the spring 33 is placed under further increased compression, or collapsed from the position shown in Figs. I and II to that of Fig. III, between the head 26 of the valve stem 21 and the cooperative abutment afforded by the inner end wall 29 of the retainer device 28. Now, it will be equally well apparent that when the motivating medium is shut-off and the cylinder 5 is freed of its pressure, by escape through the opened exhaust port 19, the spring 33 will exert its force and return the valve stem 21 to the normal position of Figs. I and II, thereby drawing with it the actuator piston 14 and hollow valve 17; and, incidentally fully retracting the "tip" 12 of said piston clear of the lobe cam convexed edges 9, 10, so that the bell is left free to oscillate or swing into plumb position, under the influence of the buffer device 35 as explained in the patent hereinbefore cited. Incidentally, it is to be particularly remarked that when the bell is in neutral position or plumb that the point 34 of the lobe cam 8 is out of alignment or in spaced planar relation to the "tip" 12 of the actuator piston 14, so that upon restarting the bell ringing cycle said piston is always in a position for movement into operative engagement with the cam 8.

From the foregoing it is thought the merits and advantages of our present improvements will be fully comprehended, while it is to be further understood minor changes and modifications may be effected without departing from the spirit and scope of the following claims.

Having thus described our invention, we claim:

1. In bell ringing mechanism with a cam on the swinging axis of the bell and comprising a cylinder having an open end confronting said cam, an actuator piston reciprocative in the cylinder and intermittently coactive with the cam to effect ringing of the bell, and a hollow valve in the cylinder behind the piston and movable thereby to control admission and exhaust of motivating medium into and from the cylinder for imparting power and return strokes to the actuator piston, the combination of means for coaction with

the hollow valve to move it forwardly on the power stroke and effective to automatically retract the piston and valve into proper starting location on the return stroke, whereby the bell is left free to oscillate into plumb position after each ringing cycle. 5

2. In bell ringing mechanism with a radial cam on the swinging axis of the bell, the combination of a cylinder having an open end confronting the cam, an actuator piston reciprocative in the cylinder and intermittently coactive with the cam to effect ringing of the bell, a hollow valve in the cylinder behind the piston and movable thereby to control admission and exhaust of motivating medium into and from the cylinder for imparting power and return strokes to the actuator piston, a member axially secured to the actuator piston having a shoulder for coaction with the hollow valve to move the latter forwardly, and means subject to compression during the power stroke 10 of the piston effective to retract said piston and the valve during their return movement to proper starting location, whereby the bell is left free to swing into plumb position after each ringing cycle. 25

3. In bell ringing mechanism with a radial cam on the swinging axis of the bell, the combination of a cylinder having an open end confronting the cam, an actuator piston reciprocative in the cylinder and intermittently coactive with the cam 30 to effect ringing of the bell, a hollow valve in the cylinder behind the piston and movable thereby to control admission and exhaust of motivating medium into and from the cylinder for imparting power and return strokes to the actuator piston, a stem axially secured to the actuator piston embodying an enlarged section affording a shoulder for coaction with the apertured inner end of the hollow valve for moving the latter forwardly, a cupped retainer device having a wall at one 35 end apertured for slidable passage of the stem enlarged section and a circumferential flange at the other end, said flange serving for securement of the retainer device concentrically within the cylinder aforesaid and a spring in compression 40 about the stem enlarged section intermediate the retainer device apertured end and a head at the outer end of such enlarged section, whereby the piston and valve are automatically returned to proper starting position after each power stroke 45 and the bell is left free to swing plumb after each ringing cycle. 50
